BALL COCK VALVE

Benjamin J. Blumberg, New York, N. Y.

Application January 12, 1951, Serial No. 205,693

2 Claims. (Cl. 137—218)

1

The present invention relates to a ball cock valve, particularly of the type used in connection with toilet flushing tanks or the like.

The present invention is directed primarily to the provision of a ball cock valve of the character described which will not siphon any of the water from the flush tank back into the water line at the conclusion of the flushing and will also be noiseless in its operation, eliminating the hissing sound that generally accompanies the flushing operation.

The present invention is also directed to the provision of improved float and lever means for the operation of the ball cock valve which is easily and accurately adjustable for limiting the volume of water expended in the flushing operation.

I am well aware that anti-siphon and anti-noise ball cock valves of the character to which the present invention relates have heretofore been made. However, as far as I have been able to ascertain, such ball cock valves of the prior art have operated on the water pressure principle, depending for their anti-noise and anti-siphon function upon the water pressure or vacuum created in the system to operate an air admitting valve to either open or close it against gravity as the case may be. Such ball cock valves of the prior art have, therefore, been indirect in their anti-noise and anti-siphon action and more or less gradual in their operation so that they were incompletely effective in operation, and not always reliable in action. They could also easily jam and become inoperative, independently of the water circulation through the valve.

It is the object of the present invention to provide a ball cock valve of the character described in which the noise eliminating and the siphon preventing means is directly and positively effected simultaneously with the operation of the water admitting valve by the variation in water level in the flush tank and by the same mechanical means, to thereby insure the positive and effective operation of such noise and siphon preventing whenever the ball cock valve itself functions and to make the operation of such means completely effective to prevent any residual noise or siphoning.

It is also an object of the present invention to provide a combination of the ball cock valve of the character described with a float connection which is more directly and positively responsive to the changing water level in a flush tank to thereby make the action of the ball cock and its

2

anti-siphon and anti-noise mechanism more accurate and positive in operation.

It is another object of the present invention to provide a ball cock valve of the character described which is of relatively simple construction, and which is made of a minimum number of parts and therefore strong and durable and least likely to get out of order, and which is simple and easy to install and easy and convenient to operate.

The foregoing and other advantages and superiorities of the ball cock valve and float of the present invention will become more readily apparent to those skilled in the art from the embodiment thereof shown in the accompanying drawing and from the description following. It is to be understood, however, that such embodiment is shown by way of illustration only, to make the principles and practice of the invention more readily comprehensible, and without any intent of limiting the invention to the specific details therein shown.

In the drawings:

Fig. 1 is a fragmentary vertical sectional view, partly in elevation, showing the ball cock valve of the present invention as connected to a water system and to an actuating float, with the water valve in shut off position;

Fig. 2 is a similar view of the valve of the present invention with the valve shown in water admitting position;

Fig. 3 is a bottom plan view of the valve; Fig. 4 is a section taken on line 4—4 of Fig. 2; Fig. 5 is a section taken on line 5—5 of Fig. 2; Fig. 6 is a vertical section taken through the water valve cylinder on line 6—6 of Fig. 1;

Fig. 7 is a section taken on line 7—7 of Fig. 2; and

Fig. 8 is a section taken on line 8—8 of Fig. 1.

Generally stated, the invention consists of a pair of integrally formed intercommunicating cylindrical valve housings, one of which seats the water valve and the other an air valve, and a pivoted lever arm which is raised and lowered by the water level in the tank in conventional manner and which is connected to the two valves in a manner to simultaneously open either of the valves and shut the other. The invention also includes a float and lever arrangement which are in rigid adjustable association with each other and with the valve to render the action of the valve more positive, more exacting and accurate.

Referring more specifically to the ball cock valve of the present invention, and with particu-

lar reference to the embodiment thereof illustrated in the accompanying drawings, such valve comprises a dual, integrally formed, preferably integrally cast metal housing, generally designated as 10, and consisting of a pair of valve cylinders, 11 and 12, preferably coextensive in height, separated by a common wall, 13.

One of the cylinders 11, for housing the water admitting valve has an upper open ended, cylindrical bore section 14, and a lower, enlarged bore section 15. The bottom of the cylinder 11 is substantially completely open and is threaded, as at 16, to receive a plug coupling 17, having the longitudinal passageway 18, therethrough and a threaded intermediate section 19, adapted to engage in the threads 17, an enlarged lower section 20, adapted to overlie the bottom edges of the cylinder 11, and a reduced tubular upper or nipple section 21, extending into the cylinder section 15 and preferably formed with beveled outer edges 22. The portion of the coupling passageway 18 within the enlarged bottom section 20 thereof may be enlarged and threaded, as at 23, to receive the threaded end of a leader pipe 24, connecting it to the water system.

The cylinder 12 is formed of uniform bore throughout, is open at the top and is preferably provided with a bottom wall 25. The cylinder 12 communicates with the cylinder 11 through the opening 27, formed at the bottom of the separating wall 13. The bottom wall 25 of the cylinder 12 is provided with a tapped opening 28, in which may be threaded the outlet pipe 29, for the water entering the cylinder 12 from the cylinder 11 through the opening 27.

A portion of the wall of the cylinder 12, from about a distance $\frac{1}{4}$ of its height from its top to about $\frac{1}{2}$ of its height may be pushed out, with its bottom edge severed from the cylinder wall, to form a tapering coping 30, leaving an opening 31, connecting the interior of the cylinder 12 with the exterior; the lower edge of the coping 30 being preferably supported against the lower wall portion of the cylinder 12 by connecting webs 32.

Arranged within the cylinder 11, and fitting snugly therewithin, is a water valve piston 35. The piston 35 is preferably formed with a central annular groove 36, forming a seat for a ring washer 37. The lower end of the piston 35 may be reduced in thickness and threaded to receive a threaded coupling 38, having an inwardly directed downwardly tapering flange 39, at its bottom forming shoulders adapted to hold a washer 40, against the bottom end of the piston 35 and forming a downwardly flaring opening below the washer 40 in position to overlie the beveled end of the nipple 21, with the washer in position to set on the water admitting opening thereof.

The cylinder 12 may have arranged and snugly fitted therewithin an inverted cup-shaped cylindrical piston 42, having the top wall 43, and the depending side wall 44. The side wall 44 may have a plurality of milled-out openings 45, in its upper portion, preferably adjacent the top wall 43, which are adapted to be moved in and out of register with the opening 31 in the valve cylinder 12 for admitting air into it and shutting out air therefrom.

The cylinder 11 may have cast integrally therewith and preferably on the side opposed to the wall 13 a preferably forked substantially L-shaped bracket 47, extending above the cylinders 11 and 12. The bracket arm 47 may have pivoted thereon, intermediate its ends, a lever 75

arm 49, as by a pivot pin or rivet 50, which may be threaded, passing through the arms of the forked bracket 47 and through the lever 49 through suitable apertures formed in them.

The lever 49 may engage within an ear 52, formed on the top of the piston 35 and may have its end pivotally connected within the forked upper end of a link 53, as by means of the pin 54; the lower end of such link being pivotally secured, as by pin 55, between the spaced upright lugs 56 formed on the top of the wall 43. An arcuate boss 57 may be formed on the top of the piston 35, within the ear 52, to form a close fit for the lever 49 within such ear and on which the lever 49 may bear to lower the piston 35, without too much play.

The other end of the lever 49 may be provided with a vertical, threaded opening 58, therethrough within which may be adjustably arranged a threaded rod 59, vertically set into a float 60; the rod 59 preferably formed with a slotted end 61 to enable its ready and convenient adjustment by means of a screw driver for adjusting the desired water level in a flush tank.

If desired, the lever arm 49 may be provided with a longitudinal boss, 62, within which may be formed a longitudinal, threaded opening, 63, to receive the end of the rod of a conventionally arranged float, in a manner readily understood and not thought necessary to be specifically illustrated or described.

A relatively small threaded outlet opening, 35, may be provided in the wall of the enlarged bore section 15 of the cylinder 11 to receive an outlet pipe for the overflow of excess water that may be admitted thereto.

Having thus described the construction of the ball cock valve of the present invention, its operation will now be clear to anyone skilled in the art. It will be readily understood that the water piston 35 and the air piston 42 may be so constructed as to length or height and so arranged within their respective cylinders and so linked to the lever arm 49, that when the float 60 is lowered by the receding water level

in the flush tank, the end of the lever 49 engaging the piston 35 and the piston 42 will rise. This will simultaneously raise the piston 35 from the nipple 21, to open the water valve for admitting the water back into the flush tank, and simultaneously raise the piston 42 to move its openings 45 out of register with the opening 31 into the cylinder 12 to shut out any incoming air and prevent outflow of water therethrough.

When the water level in the flush tank is then built up to raise the float 60 and its associated end of the lever arm 49, the opposed end of the lever arm will be depressed, to lower the piston 35 into valve closing position and simultaneously and directly lower the piston 42

to bring its openings 45 in register with the opening 31 in the cylinder 12, to admit air into the system to thereby prevent back suction as well as the hissing noise that is associated with it.

This completes the description of the ball cock valve of the present invention and the manner in which it operates. It will be readily apparent that such ball cock valve is highly effective and efficient for its purpose of eliminating back suction as well as the associated noise because the air admitting part of the valve is directly and positively operated in the same manner as the water admitting part thereof and by the same force and means, so that the two are actuated

simultaneously and function simultaneously but independently of the action of the other.

It will also be apparent that the ball cock valve of the present invention is of highly simplified construction involving but a few simple and sturdy movable parts that are not likely to go out of order. It will likewise be apparent that the ball cock valve of the present invention does not require flush tanks as wide as the conventional ball cock valve installations do, by reason of the arrangement of the float with respect to the valve operating lever.

It will be further apparent that numerous variations and modifications may be made in the ball cock valve of the present invention, in accordance with the principles of the invention hereinabove set forth and without the use of any inventive ingenuity. I desire, therefore, to be protected for any and all such variations and modifications that may be made within the spirit of the present invention and the scope of the claims hereto appended.

What I claim is:

1. A ball cock valve comprising a pair of parallel, integrally formed cylindrical valve housings separated by a common wall, one of said valve housings being open-ended and having an enlarged bottom portion, a coupling having a passageway therethrough threaded into said enlarged bottom portion, said coupling having a nipple portion projecting within said enlarged bottom portion for admission of water thereto, said common wall having an opening formed therewithin opposite said enlarged bottom portion for the passage of water therefrom into the other of said valve housings, a cylindrical piston valve arranged within said first valve housing for reciprocal movement therewithin to open and close said nipple, said second valve housing open at its top and having a bottom wall and a water outlet formed in said bottom wall, said second housing having air admitting ports formed in its side wall, an inverted cup-shaped cylinder valve arranged within said second housing for reciprocal movement therein, said cylinder valve having openings formed in the side wall thereof adapted to be brought in and out of register with said air ports, a pivotally supported lever engaging each

of said valves to be simultaneously moved thereby for disposal in alternately operative position.

2. A ball cock valve comprising a pair of parallel, integrally formed cylindrical valve housings separated by a common wall, one of said valve housings being open-ended and having an enlarged bottom portion, a coupling threaded into said enlarged bottom portion, said coupling having a passageway formed therethrough and terminating in a nipple extending into said enlarged portion, said common wall having an opening formed therein opposite said enlarged portion for the passage of water therefrom into the other of said valve housings, a piston valve arranged within said first valve housing for reciprocal movement therewithin to open and shut said passageway through said nipple, said second valve housing open at its top and having a bottom wall and a water outlet formed in said bottom wall, said second housing having air ports formed in its side wall, portions of said side wall being outwardly tapered to form a coping over said air ports, an inverted cup-shaped cylinder valve arranged within said second housing for reciprocal movement therein, said cylinder valve having openings formed in the side wall adapted to be brought in and out of register with said air ports, a lever pivotally supported over said valve housings and engaging each of said valves, said valves positioned within their respective housings and engaging said lever in arrangement to be simultaneously brought in alternating operative position upon each tilting of the lever.
